GEORGE S. HOOVER, OF WELLSBURG, WEST VIRGINIA

MANUFACTURE OF VALVES IN PAPER SACKS

Application filed December 7, 1929. Serial No. 412,431.

In preparing certain commodities for the market, such as cement or other merchandise of a powdered or granular form, it is the practice to fill sacks with the material through the use of a pneumatic blast flowing through a delivery nozzle which is inserted through one corner of the sack or bag to be filled. The bags or sacks are constructed with corner flaps or valves which are folded inwardly when the bag is made so that an opening is left through which the filling nozzle may be inserted and the pressure created within the bag by the air blast and by the commodity with which it is filled serves to automatically close the flap so that loss of the merchandise does not occur. The valved bags or sacks are at present constructed by automatic machinery which forms a long continuous tube and makes cuts at intervals across the tube of such form that the separated sections of the tube may be easily so folded as to produce the desired flap or valve, the open ends of the cut sections of the tubes being simultaneously closed by the use of double sewing machines. At the present time, so far as I am aware, the flaps or valves are formed solely by hand, and it is the object of the present invention to provide means for mechanically forming the flaps as the tube passes to the separating knife and to produce the flaps or valves rapidly and efficiently. One form of mechanism for accomplishing this result is illustrated in the accompanying drawings and will be hereinafter fully described, the invention residing in certain novel features which will be particularly defined in the appended claims.

In the drawings:

Figure 1 is a plan view, partly broken away, of a machine embodying my invention,

Fig. 2 is a longitudinal section on the line 2—2 of Fig. 1,

Fig. 3 is a transverse section on the line 3—3 of Fig. 1,

Fig. 4 is an enlarged plan view, partly in horizontal section, of the working elements of the invention,

Fig. 5 is a further enlarged view showing parts of the mechanism shown in Fig. 4 but in a different position.

Fig. 6 is a section on the line 6—6 of Fig. 4,

Fig. 7 is a transverse section on the line 7—7 of Fig. 4,

Fig. 8 is an enlarged detail section on the line 8—8 of Fig. 1,

Fig. 9 is a detail perspective view showing cooperating members of the flap-forming mechanism,

Fig. 10 is a detail sectional elevation of a roller which forms a part of the apparatus, and

Fig. 11 is a detail sectional elevation of a portion of a bag.

Referring to Fig. 1, there is shown a machine of the same general type as machines now in use for forming the tube from which the bags are subsequently produced. These machines comprise a suitable supporting frame 1 and formers, indicated at 2, whereby a blank strip 3 of heavy paper has its edges brought together and coated with adhesive so as to form a long tube, indicated at 4, which is subsequently separated into sections each of which has the length intended for the separate bags. The formers 2 are indicated in the drawings in a conventional manner only and the devices for applying adhesive are omitted inasmuch as a showing of the same is not necessary for an understanding of my invention. The formed tube is caused to travel through the machine by passing between sets of rollers 5 and 6, the rear rollers 6 being driven at a slightly less speed than the forward rollers 5 in order to permit the tube to be expanded during the formation of the valve, the valve being formed at a point in the tube between the two sets of rollers, as will be understood upon reference to Fig. 1. The rollers may be driven through any convenient or approved form of gearing and the front and rear rollers may be operatively connected through sprocket gearing or the equivalent, indicated at 7. The rollers 5 are provided with surfaces of cushioning material, such as rubber indicated at 8, in order to accommodate the seam which is formed in the tube during the manufacture of the same and said rollers are each provided near one end with an annular groove 10, the purpose of which will presently appear.

100

The rollers 5 are preferably formed with wooden bodies at one end, as indicated at 11, and the grooves 10 are formed in said wooden portions, while a knife 9 is set in the wooden portion 11 of the rearmost of said rollers. This knife 9 is provided with a serrated cutting edge, as indicated at 12, and is of an offset or Z contour having two end parallel portions extending longitudinally of the roll and 10 an intermediate transverse connecting portion extending circumferentially of the roll, as clearly shown in Fig. 10. This formation of the knife or cutter is necessary to produce the desired cut in the bag. One of the rear rolls 6 has a straight knife, indicated at 13, set therein and the parts are so proportioned and timed that the knife 13 will assume an active position just as the cut previously made by the knife 9 is alined therewith so that the 15 action of the knife 13 is to separate the tube into sections of the length desired in the finished bag.

Secured at one end to the main supporting frame, as shown at 14, is a guiding and supporting member which has a tubular formation, indicated at 15, and extends lengthwise of the machine and centrally thereof so that as the tube 4 is formed it will pass around this guide tube 15 and encircle the same. As 20 shown in Fig. 1, the tube 15 extends to a point between the sets of rolls 5 and 6 and at its terminal is secured to a head 16 having a lateral offset 17 on one side which engages the adjacent side of the tube and forms a support and guide for the same, the outer side or edge of the offset being longitudinally grooved, as shown at 18, whereby it will accommodate the usual crease or fold formed 25 in the tube as the latter is produced by the manipulation of the blank, said crease or fold being indicated at 19 in Fig. 7, upon reference to which figure it will be understood that the grooved edge 18 of the head supports the crease or fold in a partly open condition while 30 maintaining the bag at its full width. At the side of the head 16 opposite the offset 17, I secure laterally extending arms or posts 20, the outer ends of which fit within tubes 21 which are secured at their outer ends to a 35 guiding and supporting bar 22 which has its outer edge longitudinally grooved, as seen clearly in Fig. 7, whereby to accommodate and support the fold 23 formed in the corresponding side of the tube 4 and cooperate 40 with the offset 17 to maintain the bag at its full width. The tubular members or sockets 21 are held slidably to the posts or arms 20 by set screws or studs 24 secured in the posts or arms and passing through slots 25 in the 45 sides of the sockets, as shown in Fig. 4 and as will be understood, expansion springs 123 being housed in the sockets and maintaining the bar 22 in engagement with the fold in the bag tube. In forming the flap or valve, 50 the tube 4 is temporarily expanded and the

yieldable mounting of the guide 22 furnishes the needed support for the side of the bag tube while at the same time permitting it to flex somewhat and accommodate the temporary vertical expansion of the tube. It 70 will be noted that the head 16 projects longitudinally beyond the offset 17 and the end of said offset, consequently, serves as a stop to limit the retracting movement of the flap or valve-forming elements. 75

Extending through the guide tube 15 is a reciprocatory bar or slide 26 to the outer end of which is attached a chain or other flexible element 27 passing over guide pulleys 28 on the main frame and having a weight 29 secured thereto whereby the bar or slide will be automatically retracted after it has been drawn forward during the formation of a valve and by the action of the valve-forming elements. At its forward end the bar 26 is formed with a lateral lug 30 which projects through a slot or notch 31 in the side of the guide tube 15 adjacent the head 16 and to said lateral lug is rigidly secured a rack bar 32, the rack bar being located below the head, as shown in Fig. 7. The rack bar carries an anvil or former 33 which extends laterally the same distance as the offset 17 and normally abuts the forward end of said offset, as shown in Figs. 1, 4 and 5. The outer side of the anvil is formed with a longitudinal V-shaped groove 34 which is adapted to engage and support the fold 19 of the bag tube, and at its forward end it is formed with upwardly and downwardly diverging horns 35 which provide a space for the accommodation of the flap-forming elements and which cooperate with said elements in the formation of the flap. The inner side of the anvil is constructed with a short rib 36 fitting between the upper and lower sides of the head 16, as shown in Fig. 7, and provided on its upper and lower surfaces with longitudinal ridges 37 which engage longitudinal grooves 38 provided therefor in the opposed inner faces of the head. These ridges and the grooves 38 by their inter-engagement serve to maintain the proper relation of the head and the anvil and to hold the anvil to a rectilinear path in its movement. Pivotedly mounted within the head 16 is a lever 39 having the arcuate form shown clearly in Figs. 4 and 5, whereby it may pass around the front end of the anvil to maintain engagement with the side of the bag tube, the free end of the lever being equipped with a roller 40 whereby frictional resistance to the travel of the tube will be minimized. On the inner end of the lever is formed a gear 41 concentric with its fulcrum and this gear forms one member of a train of gearing, shown at 42, which has a terminal member 43 below the head (see Fig. 7) meshing with the rack bar 32 and the purpose of which will later appear. Cooperating 120 with the roller 40 and the end of the lever 125

39 is a presser finger 44 which is disposed at the outer side of the bag tube and bears thereon, as shown in Fig. 4, so that as long as an uncut portion of the tube is passing between 5 the finger and the lever the finger and lever will be inactive, as will be understood upon reference to Fig. 4. Whenever a cut in the tube, indicated at 45, reaches the finger, the resistance to the finger will be relieved and 10 the finger at once rocks inwardly so as to push the material of the tube inwardly, as shown in Fig. 5, to form the flap. The finger 44 is pivoted upon a slide 46 which has its outer end mounted in a guide bracket 47 secured 15 on the main frame, which bracket is constructed with longitudinal grooves 48 in its inner opposed faces to be engaged by a T-shaped rib 49 at the outer end of the slide 46, as shown in Figs. 7 and 9. The finger 44 is 20 pivoted within an opening or recess 50 formed in the inner portion of the slide 46 and a torsion spring 51, engaged with the slide and the finger, serves to swing the finger inwardly when it is relieved of the supporting influence 25 of the uninterrupted portion of the bag tube. As shown in Fig. 9, the working end of the finger is forked, as at 52, so that when the finger swings inwardly it may clear the roller 40 and the end of the lever 39. The 30 inner end of the slide 46 is shaped to present a right angular recess 53 to the finger 44 and the end of the lever 39 so that as the travel of the tube continues the flap, indicated at 54, will be forced into said recess and the basal 35 fold 55, shown in Fig. 11, will be positively formed. The slide is also formed with a rearwardly and outwardly curved lip or flange 56 whereby the side of the bag at the base of the flap will be relieved of possible rupture 40 by contact with a sharp edge or surface.

It will be understood that the tube 4 from which the bags are produced is caused to travel continuously through the machine by the action of the rollers 5 and 6. When the 45 cut 45 is brought to the finger 44 and the lever 39, the advancing side of the cut will, of course, pass readily between the lever and the finger. Inasmuch, however, as the wall or side of the tube is the only support for 50 the finger, when the trailing side of the cut reaches the finger, the spring 51 at once throws the finger inwardly, as shown in Fig. 5, so that the portion of the side of the tube against which the finger bears is pushed inwardly to start the formation of the flap. The forked construction of the finger causes 55 it to clear the roller 40 and the end of the lever 39 so that the started flap is carried to the inner side of the lever, as will be understood from Fig. 5. The travel of the tube, however, is uninterrupted and, consequently, the flap or the partly folded flap is brought against the inner side of the lever and at once acts upon the same to cause it to swing about 60 its own fulcrum, thereby setting in motion the train of gearing 42 and causing the rack bar 32 to travel with the tube, the end of the lever being received in the recess 53 so that the basal fold 55 of the valve is formed. At 65 a point in advance of the rollers 5, a short post 57 rises from the upper side of the bar 26 through a slot in the top of the guide tube 15, as shown in Figs. 2 and 3, and at the upper end of this short post 57 is a lateral stud 58 engaging in a fork 59 at the lower end of a rocking arm 60 which is secured to and depends from a rock shaft 61 disposed transversely of the machine and journaled at its ends in pedestals or standards 62 rising from the main frame. Near one end of said shaft 61 a second rocking arm 63 is secured to and depends therefrom and the lower end of this arm 63 is formed into a fork 64 in which is engaged a stud 65 on the upper end of a post 66 rigid with and rising from a sliding bar 67 which is mounted in guiding supports 68 on the main frame and bracket 47, respectively. The forward end of the bar 67 is secured in the slide 46, as shown most clearly in Fig. 5. Consequently, the slide 46 will be caused to move forwardly with the rack bar 32 and the bar 26 and, therefore, the inner end of the slide will be carried forwardly with the end of the lever 39 so that the basal fold 55 of the flap will be compressed between the end of the lever and the back wall of the recess 53 and will be positively completed. When the travel of the bag tube 4 carries the folded flap beyond the range of the arc described by the lever 39 as it swings with the flap, the force actuating the lever will cease and the lever or finger and the slides will be at once returned to the initial normal position through the influence of the weight 29 and the flexible element 27 connecting said weight with the bar 26, the parts remaining in the normal position until a second cut reaches the spring-pressed finger 44 when the cycle of operations will be repeated. It will be understood that the bag tubes are formed in continuous lengths as long as the machine is operating, the end of a second blank being pasted or otherwise secured to the end of a preceding blank as the action proceeds so that there will be no interruption to the passage of the paper or other material through the machine and the consequent formation of the tube and the creation of the folds or flaps therein. The bags are completed in the usual manner after they have been separated from the tube length by the action of the knife 13. It is obvious that when the flap-forming elements 39 and 44 go into action there is an expansion of the fold formed in the side of the tube. The expansion is necessary in order to obtain the proper engagement between the tube and the parts acting thereon to form the flap and in many instances the expansion may be produced by the engagement of the anvil or former 33 and the finger and lever. I pre- 130

fer, however, to positively expand the tube and then contract or fold the same after the flap has been formed and, to that end, I provide an expander consisting of diverging, 5 preferably resilient, arms 69 which are disposed above and below and head 16 and may be secured to the offset 17 of said head. These expanding arms will, of course, be within the tube 4, as will be understood upon reference to Fig. 6, and will positively dilate the fold formed in the side of the same. The expander may be formed of separate arms but to facilitate manufacture I form it from a single piece, the two arms being connected by 10 a U-shaped shank 70. To again contract or collapse the side of the tube after the flap has been formed, there are provided the contracting bars 71 which are disposed above and below the tube and are carried by bolts 72 extending inwardly from the main frame and engaged in lugs 73 formed on the contracting arms. These bars 71 are flat strips of metal 15 or any smooth material and, as shown in Fig. 6, they converge in the direction of the travel of the tube so that the side of the tube will be refolded and compressed as is desired. Co-operating with the contractor is an idler 74 which is preferably in the form of a pinion mounted upon the main frame in such position 20 as to run in the fold of the tube so that as the tube travels past the flap-forming mechanism the fold or crease will be reformed to the same condition that it was prior to the expansion or dilation to permit the formation 25 of the flap.

In Fig. 11 is shown a portion of a bag 75 which is equipped with a valve or flap formed by the machine of my invention. It will be noted that the flap is located at one corner of 40 the bag and provides an opening through which the filling nozzle may be inserted. The ends of the bag are closed by binding strips 76 sewed thereon along the open edges and at one end the binding strip is swung around 45 so as to pass over the corner opening left by the cut in the blank and sewed, this end of the bag or sack being the bottom when the sack is filled. The filling nozzle will engage the flap so that as the nozzle is withdrawn from the filled bag the flap will be 50 drawn out or inverted to extend across the opening which would be otherwise left and thereby fully close the bag. The offset or Z-shaped formation given the cut 45 with the 55 subsequent folding of the flap will cause the ends or corners of the flap, indicated at 77, to assume a position aligned with the edges of the cut ends of the tube so that the intermediate portion of the cut will mate with the 60 cut edges of the bag and, consequently, when the stitching, indicated at 78, is applied, the ends of the flap will be secured.

By the use of my invention the completion 65 of the bags or sacks is expedited and there is no interruption to the production. Accord-

ing to present practices, the tube is cut into sack lengths and then transferred to other workers to permit the formation of the flaps, and after the flaps are formed or folded the bags are returned to a conveyer to be carried 70 to the sewing machines. With my machine the tube is not taken from the machine until it is delivered to the sewers. The mechanism is simple and compact and it is actuated by the travel of the tube from which the bags 75 are formed so that it will only operate when a flap is to be formed and at the proper location and the provision of a complicated gearing is made unnecessary.

Having thus described the invention, I 80 claim:

1. In bag-making machinery, the combination of means for forming cuts at intervals in one side portion of a continuously traveling bag tube, and means operable by engagement with a cut portion of the tube to fold one side thereof into the tube to form a valve. 85

2. In bag-making machinery, the combination of means for forming cuts at intervals in one side of a continuously traveling bag 90 tube, and means for engaging a side of the tube and laterally supporting the same, said supporting means being operable upon engagement with a cut portion of the tube to fold one side of the cut into the tube and 95 form a valve.

3. In bag-making machinery, the combination with means for forming a cut in one side of a continuously traveling bag tube, a finger engaging the outer surface of said 100 side of the tube, means for swinging said finger inwardly when a cut is presented thereto, and means disposed within the tube and cooperating with the finger and operable upon engagement with a cut portion of the tube to fold one side of the cut into the tube and form 105 a valve.

4. In bag-making machinery, the combination of means for forming a cut in one side of a bag tube, means for causing travel of the tube continuously, a finger bearing against the outer side of the tube, a cooperating swinging support within the tube bearing against the inner surface of the side of the tube, a former within the tube cooperating 110 with the finger, means for swinging the finger inwardly whereby when a cut is presented to the finger one side of the same will be folded inwardly to form a valve, and means actuated by the travel of the tube for releasing the inner support and restoring the parts 115 to normal position.

5. In bag-making machinery, the combination with means for forming a bag tube and causing continuous travel of the same, of means for forming a cut in one side of the tube at intervals, and means normally supporting said side of the tube and operable by the travel of the tube to fold one side of the 120 cut within the tube and form a valve. 125

6. In bag-making machinery, the combination of means for forming cuts at intervals in one side of a bag tube, a slide disposed at the outer side of the tube and bearing against the side of the same, a spring-pressed finger mounted on said slide and bearing against the side of the tube to be supported by uninterrupted portions of the same and swing inwardly when a cut is presented thereto, means disposed within the bag tube and cooperating with the slide and the finger to shape the fold, and means whereby the last-mentioned means will be caused to travel with the tube and release the finger and restore the parts to normal position.

7. In bag-making machinery, the combination of means for making a cut in the side of a bag tube at intervals, a slide disposed at the outer side of the bag tube and having a recess in its inner end, an anvil within the tube and cooperating with said slide to support the side of the tube, a spring-pressed finger mounted in the slide and bearing against the outer side of the tube to swing inwardly when a cut is presented thereto and fold the side of the bag into a valve, a swinging pressure member also disposed within the tube and adapted to enter the recess in the outer end of the slide to compress the valve, and means actuated by the travel of the tube to release said last-mentioned means and restore the parts to normal position.

8. In bag-making machinery, the combination with means for forming a bag tube and effecting continuous travel of the same, means for making cuts in one side of the tube at intervals, a slide mounted adjacent the tube and bearing against the outer side of the same, a spring-pressed finger carried by the slide and engaging the outer side of the tube, an anvil slidably disposed within the tube and cooperating with the slide and the finger whereby when a cut is presented to the finger a portion of the side of the tube will be folded inwardly and shaped to form a valve, a pivoted support disposed within the tube and bearing against the inner surface of the side thereof to cooperate with said finger, and means whereby the travel of the tube will actuate said support to cause travel of the slide and the anvil to permit completion of the valve and clear said support, and means for returning the parts to normal position after the valve clears said support.

9. In bag-making machinery, the combination of means for effecting continuous travel of a bag tube, means for forming cuts in one side of the tube at intervals, a guide disposed centrally within the bag tube, a head at the end of said guide to support the tube, means at the head for forming a valve in the tube, means whereby said valve-forming means upon engagement with a cut portion of the tube will operate to form the valve and then return to normal position, and a bag sup-

port yieldably mounted on the head at the opposite side of the same.

10. In bag-making machinery, the combination of means for continuously moving a bag tube, means for forming cuts in a side of the tube at intervals, a guide disposed centrally within the tube, means operating at the end of said guide and actuated by engagement with a cut portion of the tube for forming a valve therein at the cuts, means movable in the guide for returning the valve-forming means to a normal position, an expander carried by the head within the bag tube, and a contractor disposed exteriorly of the tube beyond the head.

In testimony whereof I affix my signature.
GEORGE S. HOOVER.
